UNITED STATES PATENT OFFICE.

MARVIN D. HUBBELL, OF PALATKA, FLORIDA.

BLADE HOLDER.

Application filed July 10, 1926. Serial No. 121,648.

This invention relates to blade holders and more particularly to a holder adapted to grip a safety razor blade when stropping the same.

5 One object of the invention is to so form the holder that a blade may be firmly gripped between companion strips with the portion of the blade having a cutting edge extending transversely from the holder.

10 Another object of the invention is to prevent the holder forming strips from having movement transversely of each other when assembled.

Another object of the invention is to so 15 unite the strips that they will be firmly held in engagement with each other but may be readily separated after a blade has been stropped.

The invention is illustrated in the accompanying drawings, wherein:

Figure 1 is a perspective view of the blade holder with a safety razor blade of a conventional construction held thereby;

Fig. 2 is a longitudinal sectional view 25 taken on the line 2—2 of Fig. 1;

Fig. 3 is a transverse sectional view taken on the line 3—3 of Fig. 1;

Fig. 4 is a transverse sectional view taken on the line 4—4 of Fig. 1;

30 Fig. 5 is a perspective view of the forward end portion of one of the strips from which the holder is formed;

Fig. 6 is a perspective view of the forward end portion of the second strip;

35 Fig. 7 is a transverse sectional view illustrating a slightly modified construction;

Fig. 8 is a top plan view of another modified form of blade holder;

40 Figs. 9 and 10 are perspective views of the companion strips constituting the holder shown in Fig. 8, and

Figs. 11 and 12 are transverse sectional views taken, respectively, on the lines 11—11 and 12—12 of Fig. 8.

45 The blade holder is formed of companion strips 1 and 2 which are preferably metal but may be molded or cut from other materials if so desired. These strips are rigid so that they do not bend an appreciable amount when the blade held is being stropped but should be of sufficient strength to prevent them from being broken during the stropping action. The strip 1 which rests upon the strip 2 is of such width that, 50 when in place, it extends from the inner face of the side flange 3 to the free side edge

of the strip 2 and of such thickness that its upper face will be flush with the upper face of the flange, as shown in Figs. 3 and 4.

A recess 4 is formed in the forward end 60 of the strip 1 intermediate its width, and this recess is adapted to receive a lug or arm 5 carried by the forward end of the strip 2 and provided at its upper end with a lip 6 which extends in overhanging relation to the body portion of the strip 2, as

65 shown in Fig. 5, and is adapted for overlying engagement with the forward end of the strip 1, as shown in Figs. 1 and 2. It will, therefore, be seen that this arm or lug 70 together with its lip 5 will serve to securely retain the forward end portion of the strip 1 in operative engagement with the strip 2. Slots 7 and 8 extend longitudinally of the

75 forward end portions of the two strips and register, as shown in Figs. 2 and 3, so that, when a blade 9 of the type used in a "Gem" safety razor is to be stropped, the head portion 10 of the blade may extend into the slots. Referring to Figs. 2 and 3, it will 80 be seen that the head portion of the blade is snugly received in the two slots and, therefore, the blade will be firmly held against movement longitudinally or transversely of the holder and there will be no danger of its slipping out of the proper position with respect to the holder while being stropped.

85 Pins 11, 12 and 13 project upwardly from the strip or jaw 2 in spaced relation to each other longitudinally of the strip and are received in openings 15, 16 and 17 formed in the strip or jaw 1. These pins serve not only as means for assisting in preventing the strips from having longitudinal or transverse movement relative to each other, but 90 also serve to engage other types of razor blades and prevent them from having sliding or twisting movement between the strips while being stropped. If a blade of the Gillette or Durham type is to be stropped, 100 it will be disposed between the strips with the pins 11 and 12 passing through the openings of the Gillette blade or longitudinally extending slot of the Durham Duplex blade. These blades have not been illustrated as 105 they are of a well-known construction. It will be obvious that blades other than those specifically mentioned may also be gripped between the strips and engage either with appropriate pins or have portions fitted into the slots 7 and 8 of the strips. The rear end 110 portions of the two strips or jaws should be

firmly held in engagement with each other while a blade is gripped between their forward portions and, therefore, there has been provided a latch 18 which is U-shaped in cross section, as shown in Figs. 3 and 4, and has its upper arm formed with a rearwardly extending ear 19 through which extends a pivot pin 20. The pivot pin 20 is in the form of a rivet which passes through aligned openings formed in the ear and strip 1, as shown in Fig. 2, and has heads formed at its upper and lower ends, the lower head being countersunk so that it is flush with the under face of the strip 1. It will be readily seen that after the forward end of the strip 1 has been engaged with the arm 5 and swung downwardly into engagement with the strip 2 for clamping a blade disposed between the strips the latch 18 may be swung to the position shown in Fig. 1 and its arms will grip the two strips and securely hold them in engagement with each other. The holder may then be held in one hand with the forward end portion extending from the hand and the blade stropped in the usual manner. It will also be obvious that if desired a safety razor blade may be secured between the strips, as shown in Fig. 1, and the device used as a ripping knife.

In Fig. 7, there has been illustrated a blade holder having a slightly modified construction. Referring to this figure, it will be seen that the strip 2 instead of being bent to form a flange 3 may have its corresponding side portion rolled to form a tubular sleeve 21 which extends above and below the plane of the strip and serves not only as an abutment to engage the strip 1 but also as a heel upon which the blade holder may be turned when stropping the blade.

In Figs. 8 to 12, there has been illustrated another modified form of the invention. Referring to these figures, it will be seen that the strip or section 2 instead of being bent upwardly to form an abutment flange 3 is first bent downwardly, as shown at 22, and then bent upwardly back upon itself with a portion 23 projecting above its upper face and constituting an abutment flange corresponding to the flange 3. The strip 2 in this form of the invention will, therefore, be provided at one side with a head having a depending portion 22 adapted to rest upon a strop and retain a blade gripped between the strips in proper angular relation to the strop and an upper portion 23 forming an abutment flange corresponding to the flange 3 and adapted to be engaged by the strip or section 1. The section 1 is of greater width than the section shown in Figs. 1 and 6 and has one side portion bent to form a flange 24 of a height corresponding to the flange 23 and adapted to engage the inner face thereof, as shown in Figs. 11 and 12. The strips 1 and 2 in this form of the invention are

provided with openings or slots 7 and 8 corresponding to the openings 7 and 8 of the form shown in Figs. 1 and 2 and the strip 1 is also formed with openings corresponding to the openings 15, 16 and 17 and indicated by the same reference numeral. Instead of employing rivets 11, 12 and 13 to pass through openings or recesses formed in razor blades and fit into the openings 15, 16 and 17, the strip 2 in this form has been stamped to provide lugs 25, 26 and 27. These lugs take the place of the studs 11, 12 and 13 but are formed integral with the strip instead of separate therefrom. The arm 28 carried by the strip 2 corresponds to the arm 5 and is provided with a bill or lip extension 29 but instead of being disposed intermediate the width of the strip is located adjacent the opposite side thereof from the flange 23 and is received in a recess 30 corresponding to the notch or recess 4 in the strip 1. By having the arm or hook 28 disposed at one side of the strip 2 instead of intermediate its width the strip 1 may be very easily placed in engagement with the strip 2. At their opposite ends the two strips are releasably secured to each other by a fastener corresponding to the clip 18 and pivotally mounted through the medium of a rivet 20 so that it may be swung into and out of gripping engagement with the two strips. The portions of the strips straddled by the fastener when in a gripping position are formed with recesses 31 and 32 so that the fastener does not project from the edges of the strips and will not be liable to be accidentally moved to a releasing position. Since the fastener fits into the recesses, it may cooperate with the studs to prevent the two strips from having movement longitudinally of each other. The upper edges of the flanges 23 and 24 may be rounded so that the blade holder may be readily turned upon a strop or if desired the strip from which the section 2 is formed may be of greater width and after being bent to form the upwardly projecting portion of its head have the upper portion thereof folded back upon itself and provide a rounded upper edge for the flange 23. It should also be noted that if desired a fastener 18 could be provided for the forward end portion of the holder in which case the hook or clip 28 and recess 30 could be dispensed with.

Having thus described the invention, I claim:

1. A blade holder comprising companion jaws each formed as an elongated strip, one being provided with a side flange overlapping the adjacent side edge of the other strip in abutting engagement therewith, a fastener carried by one strip adjacent one end thereof and adapted to engage the other strip and prevent movement thereof away from the first strip, said strips being formed for inter-

- locking engagement with a blade disposed therebetween with a sharpened edge portion of the blade extending from the strips at the opposite side from said flange, and a U-shaped clip pivotally carried by one of said strips adjacent the other end thereof from said lug and adapted to be swung into straddling engagement with the strips.
2. A blade holder comprising companion jaws having flat face to face contact and each formed as an elongated strip, one being provided with a side flange overlapping the side edge of the other strip, a lug extending from one strip adjacent one end thereof and having a portion to extend in overlapping relation to the other strip and prevent movement thereof away from the first strip, said strips being formed for interlocking engagement with a blade disposed therebetween with a portion extending from the strips at the opposite side from said flange, and a U-shaped fastener adapted for straddling engagement with said strips adjacent the opposite ends thereof from said lug and formed with a side arm pivoted to one strip to mount the fastener for swinging into and out of gripping engagement with the strips.
3. A blade holder comprising elongated strips adapted to be disposed one upon the other and engage opposite faces of a blade placed between the strips with the strips in interlocking engagement with the blade, one strip having a side portion bent downwardly and then upwardly to form a head having a portion projected upwardly and constituting an abutment flange, the other strip having a side portion bent upwardly to form a flange adapted to engage the abutment flange of the first strip, and means to releasably secure the strips one upon the other with portions thereof in gripping engagement with a blade disposed between them.
4. A blade holder comprising elongated strips adapted to be disposed one upon the other and engage opposite faces of a blade placed between the strips with the strips in interlocking engagement with the blade, one strip having a side portion bent downwardly and then upwardly to form a head having a portion projected upwardly and constituting an abutment, the other strip being adapted to rest upon the upper face of the first strip with a side portion engaging the abutment thereof, and means to releasably secure the strips with a blade firmly gripped between them.
5. A blade holder comprising elongated strips adapted to be disposed one upon the other and engage opposite faces of a blade placed between the strips with the strips in interlocking engagement with the blade, one strip having a side portion bent downwardly and then upwardly to form a head having a portion projected upwardly and constituting an abutment flange, the other strip being adapted to rest upon the upper face of the first strip with a side portion engaging the abutment flange thereof, and a clip adapted to straddle said strips and releasably secure them in engagement with each other, the free side portions of the strips being formed with registering recesses to receive the clips.

In testimony whereof I affix my signature.
